(57) CLAIM

I claim the ornamental design for a display packaging, as shown and described.

DESCRIPTION

FIG. 1 is a side perspective view of the display packaging;

FIG. 2 is a front view of FIG. 1;

FIG. 3 is a rear view of FIG. 1;

FIG. 4 is a left side view of FIG. 1; and,

FIG. 5 is a top view of FIG. 1.

The appearance within the unshaded circular regions of FIGS. 1-3 forms no part of the claimed design.
